(57) **CLAIM**

I claim the ornamental design for safety bolt bag, as shown.

DESCRIPTION

FIG. 1 is a front perspective view of a safety bolt bag according to an embodiment of the invention.

FIG. 2 is a front perspective view of the safety bolt bag of FIG. 1 in a closed disposition according to an embodiment of the invention.

FIG. 3 is a front perspective view of the safety bolt bag of FIG. 1 in an open disposition according to an embodiment of the invention.

FIG. 4 is a front view of the safety bolt bag of FIG. 1.

FIG. 5 is a right side view of the safety bolt bag of FIG. 1.

FIG. 6 is a rear view of the safety bolt bag of FIG. 1.

FIG. 7 is a left side view of the safety bolt bag of FIG. 1.

FIG. 8 is a top view of the safety bolt bag of FIG. 1; and,

FIG. 9 is a bottom view of the safety bolt bag of FIG. 1.

The broken lines in the drawings represent stitching and are part of the claimed design.
